UNITED STATES PATENT OFFICE.

RICHARD CLARK AND LOUIS M. CROM, OF WARSAW, OHIO.

PRINTING-PRESS.

SPECIFICATION forming part of Letters Patent No. 580,505, dated December 11, 1894.

Application filed November 15, 1893. Serial No. 491,014. (No model.)

To all whom it may concern:

Be it known that we, RICHARD CLARK and LOUIS M. CROM, citizens of the United States, residing at Warsaw, in the county of Coshc-
ton and State of Ohio, have invented a new
and useful Printing-Press, of which the following is a specification.

Our invention relates to improvements in printing presses, and to that particular class thereof employing a stationary type-bed and a traveling impression cylinder arranged thereover.

The objects of our invention are to provide a press of cheap and simple construction and of the above class, the same being so arranged as to readily receive and automatically emit or discharge the paper after printing and whose capacity for rapid printing is increased.

Various other objects and advantages of the invention will appear in the following description and the novel features thereof will be particularly pointed out in the claims.

Referring to the drawings:—Figure 1 is a plan view of a press embodying our invention. Fig. 2 is a side elevation thereof. Fig. 3 is a vertical longitudinal central sectional view. Fig. 4 is a transverse vertical sectional view. Fig. 5 is an enlarged view in cross-section of the revolving cylinder. Fig. 6 is an enlarged detail in perspective of the carriage for conveying the cylinder.

Like numerals of reference indicate like parts in all the figures of the drawings.

In the practice of our invention we employ any suitable bed-frame. In the present instance, however, we have illustrated one simple form thereof. In the construction shown we employ a pair of lower base-sills 1, from which rise standards 2 that support the longitudinally disposed upper sills 3, the sides of the frame being connected by suitable cross-bars or beams 4. The sills 3 constitute a track and are provided at their outer sides with cleats or flanges 5, whose upper edges are above the sills to retain the cylinder carrying carriage, hereinafter described, thereon. Arranged upon the frame thus constructed is the cylinder carrying carriage, and the same consists of opposite sides 6, which are reduced toward their ends, and is of a width to fit within the cleats 5. Rollers 7 are located at the four corners of the carriage and are designed to move upon the track,

which as before stated, is formed by the upper sills 3. The sides 6 are at their centers provided with bearings 8, in which are journaled the ends of a transverse shaft 9 which accommodates and passes through the impression cylinder 10. This cylinder 10 has its surface covered with any desired covering, as shown.

Standards 11 rise from the sides 6 of the cylinder carrying frame, and at their upper ends are provided with slotted lugs 12 in which are loosely mounted the opposite extremities of the axis 13 of a paper-grasping roll 14. Inasmuch as the lugs 12 are slotted, it will be seen that the roll 14 may raise and lower, but ordinarily runs in surface contact with the cylinder 10 by which it is revolved.

At opposite sides of the cylinder we mount upon the sides 6 the transverse guard-bars 15, and the same are provided at intervals with yielding substantially triangular guard-fingers 16, which are curved at their inner sides to embrace the opposite sides of the cylinder, as best shown in Figs. 5 and 6. Below these guard-bars in bearings 17 at each side of the cylinder 10, we journal loosely a pair of ink-rolls 18, whose lower surfaces are in the same plane as that of the cylinder 10. Above the ink-rolls we journal at each side of the cylinder 10, in bearings 19, the axles of a guide-roll 20.

Hinged leaves 21 are arranged upon the ends of the cylinder-carrying frame, and are disposed normally inward toward the cylinder thereof, being supported at their inner ends by cross bars 22 which span the frame at each side of the cylinder, and complete flies 90 on which the printed sheets are allowed to accumulate.

Opposite superimposed frames 23 are horizontally disposed above the opposite ends of the framework of the press, and these frames support inclined feed-tables 24 which decline from their outer ends toward their inner ends and have extended in front of such ends the substantially horizontal extensions or plates 24^a. Each feed-table is provided at opposite sides or ends with arms 25 that are inwardly disposed and connected at their inner ends and have upturned cam or hook-shaped ends 26. Each frame 23 comprises in its make-up a cross-bar 27, and to each cross-bar is attached a pair of coiled springs 28. Pairs of

- tapes 29 are connected at their extremities to the inner ends of these coiled-springs, pass over and around the rolls 20, and are connected thereto. The rolls 20 are connected by intermediate guide-tapes 30 which are wound reversely thereon so that the rolls revolving in the same direction will cause the tapes to wind upon one of them and unwind from its companion.
- At the center of the framework we locate in the cross-bars 4 of the bed-frame vertical adjusting-screws 31 whose lower ends are so shaped as to receive a wrench. The upper ends of these screws are swiveled to the under side of the type-bed 32. At each side of the type-bed and supported by cleats 33 we locate inking-tables 34 which are in a plane with the type-bed. Paper-receiving tables 35 occupy the ends of the framework below the frames 23.
- Any means may be provided for reciprocating the cylinder-carrying carriage over the type-bed. In the present instance, however, we have illustrated one form which we will proceed to describe. We locate in transversely opposite pairs of bearings 36 crank-shafts 37, connecting the two by means of an intermediate rod 38^a. Both ends of one of the crank-shafts 37 are extended to form rock-arms 38, which by means of links 39, shown in Figs. 1 and 2, are loosely connected with the extended ends of the shaft 9 of the impression cylinder. The remaining shaft 36 has one or both of its ends extended, and is designed to serve as a handle 39^a where the press is operated by hand, or to be connected with any suitable motor for vibrating the same.
- A pair of hangers 40 depend from the opposite sides of each of the feed-tables, and being provided with bearings accommodate a transverse shaft 42 located under each of said tables. The intermediate portion of each shaft is upwardly cranked, as at 43, and passes through an elongated slot 44 to a point above the base 23 of each feed-table. One of the outer ends of each shaft 42 declines toward the center of the machine forming an arm 45, the extremity of which is inclined or slightly upwardly bent as at 46 and arranged in the path of the journal 9 of the cylinder. The opposite sides of the inclined feed-tables 24 are slotted, as at 47, and in the same there are mounted for movement transversely disposed slide-bars 48, which at their centers are connected to and adapted to be actuated in one direction by the crank portions 43 of the shafts 42. It is to the end of these slide-bars 48 that the arms 25 are connected.
- In the operation, the paper is fed by attendants from the inclined feed-tables 24 to points over the edges of the extensions 24^a. The cylinder-carriage advances toward the projecting paper, and the journal 9 which projects beyond the arm 39 thereof strikes the inclined end 46 of the adjacent arm 45, causing the same to elevate and hence rock the
- shaft 41. This action of the shaft 41 allows the arms 25 to recede in advance of the approaching cylinder until it has reached the limit of its backward movement. In the meantime, the paper-grasping roll 14 has arrived in contact with the cam ends 26 of said arms 25, so that as will be obvious, the roll 14 is caused to rise and hence passes over the end of the paper on the plate or table extension 24^a. As the carriage recedes the paper-roll 14 travels down the cam ends 26 of the arms 25 and engages with the paper, clamping it upon the revolving cylinder. The weight of the arms 45 is sufficient to return the parts to their normal position. The cylinder, it will be observed, is revolved in that it runs in contact with the track 3, and the tapes 30 move under the cylinder in the same direction as the travel of the latter, so that the sheet of paper engaged by the paper-grasping roll 14 is fed to the fingers of the cylinder and continues under the fingers until it arrives in contact with the guide-tapes, which continue the movement of the paper and carry the same under the cylinder to the opposite side thereof. Of course when the paper arrives under the cylinder it is in contact with the type, so that an impression is made upon one side of the paper. At this point the guide-tapes 30 conduct the paper from under the cylinder and deliver it upon the leaves 21. By this time the carriage is at the opposite end of the machine, where the operation described is repeated, and in moving from this point to the starting point the second sheet is printed and delivered. At intervals when a number of sheets have accumulated the leaves 21 are reversed and dump the contents upon the tables at the ends of the machine. The inking-rolls, it will be seen, travel over the ink-tables 34 and serve to supply the face of the type with the necessary ink. The coiled springs 28 give tension to the tapes 29 and serve to revolve the guide-rolls 20, and aid in the operation of the guide-tapes 30.
- It will thus be seen that we have provided a machine adapted to rapidly print and automatically feed or carry through the press the successive sheets of paper, the said machine being of cheap and simple construction, comprising few parts, and those of simple formation.
- We do not limit our invention to the precise details of construction herein shown and described, but hold that we may vary the same to any degree and extent within the knowledge of the skilled mechanic. At this point further attention is directed to the manner of feeding the unprinted sheets from the opposite feed tables to the impression cylinder. It has already been noted that the operator or feeder manipulates the unprinted sheets on the tables 24 so as to bring the edges of the same over or slightly beyond the edges of the table extensions or plates 24^a, and toward the approaching impression cylinder. When

the impression cylinder approaches the sheet of paper thus positioned, the paper roll 14, engages with the upturned cam or hook shaped ends 26 of the movable arms 25 at that end of the machine, and the shape of these ends will cause the roller 14 to raise above the paper, which is held by the feeder, and to pass to a position over the extensions or plates 24^a. Just before this has taken place the arm 45 toward which the cylinder has approached has been lifted by the engagement of one end of the journal 9, therewith, so as to move the upwardly disposed crank portion 43, of the shaft 42 in a direction which relieves the weight of the arm 45 from the slide bar 48 connecting one end of the arms 25, so that there will be nothing to interfere with the paper roll 14, carried by the carriage, from pushing the arms 25 in front of the same, as it rises up the cam ends 26, this movement being necessary to carry the paper roll above the sheet of paper and back from the edge thereof. As the impression cylinder commences to retreat from the feeding table, which has just been referred to, the paper roll 14 travels down the cam ends 26 of the arms 25, and rolls over the sheet of paper, which will not move until the said roller reaches the edge of the feed table or at least the extension 24^a, thereof, at which time the friction of the small roller on the cylinder will cause the paper to be rolled between the roller and cylinder and moved under the guides at one side of the cylinder, until caught by the tapes passing under the cylinder, and since the carriage is during this time moving toward the opposite feed table, an impression will be made on the sheet of paper and the same delivered to one of the flies. It will of course be understood that when the carriage carrying the impression cylinder leaves one of the tables, the arm 45 at that end will lower, and will of its own weight again project the arms 25 inwardly to dispose the cam ends 26 beyond the inner edge of the table extension or plate.

Having described our invention, what we claim is—

1. In a printing press of the class described, the combination with a frame-work having a track, a type-bed arranged within the track, stationary ink-tables arranged at opposite sides of the type bed and within the track, and inclined feed tables at opposite ends of the framework; of an intermediate carriage arranged to travel over the track between the opposite feed tables, an impression cylinder journaled centrally in the carriage, yielding triangularly-shaped paper guiding fingers fixedly positioned at both sides of the cylinder and having inner curved portions lying close thereto, loose rolls journaled at opposite sides of the cylinder, guide tapes reversely wound upon the rolls and passing under the cylinder, tension tapes winding on the ends of said loose rolls and connected at their outer ends to a fixed part of the framework, the op-

posite pairs of inking rolls journaled in the carriage, the stationary flies pivotally mounted on the carriage at one side of the loose rolls, and means for reciprocating said carriage, substantially as set forth.

2. In a printing-press, the combination with a framework having a track, a type-bed arranged in the track, and ink-tables located at opposite sides of the type-base, of a carriage mounted for movement upon the track, an impression cylinder journaled in the carriage, yielding triangularly shaped paper-guiding fingers at each side of the platen, loose rolls journaled at opposite sides of the platen, guide-tapes reversely wound upon the rolls and passing under the platen, tension-tapes passing over the ends of the rolls, and coiled-springs connected with the outer ends of these tapes and fastened to a fixed part of the framework, substantially as specified.

3. In a printing-press, the combination with a framework, a movable carriage arranged thereon, means for operating the carriage, a revolving cylinder arranged in the carriage, a superimposed paper-roll, and a type-bed below the revolving cylinder, of a feed-table at the end of the frame, bearings at the opposite sides of the table, a transverse crank-shaft journaled in the bearings and having its crank-portion projecting above the face of the table, a gravity-arm at one end of the crank-shaft and extending forward and having an inclined end arranged in the path of the projection on the carriage, a slide-bar arranged upon the feed-table and connected with the cranked portion of the crank-shaft, and forwardly disposed arms extending from the bar and having inclined cam ends arranged in the path of the paper-roll, substantially as specified.

4. In a printing-press, the combination with the oblong frame, the movable carriage, the revolving cylinder arranged therein, the superimposed paper-roll, and means for operating the carriage, of the opposite inclined feed-tables 24 supported on the bases 23 having elongated slots, the opposite hangers 40 having transversely opposite bearings, the transverse shafts arranged in the bearings and having intermediate cranked portions extending through the slots and their outer ends bent to form the arms 45 having the inclined extremities 46 arranged in the path of the travel of the platen, the slide-bars 48 supporting the tables 24 and connected to the cranked portions, and the arms 25 at the ends of the slide-bars and provided with cam portions 26, substantially as specified.

In testimony that we claim the foregoing as our own we have hereto affixed our signatures in the presence of two witnesses.
